UNITED STATES PATENT OFFICE.

THURE E. DAHL, OF NEW YORK, N. Y.

DESIGN FOR A GLOBE FOR LIGHTING FIXTURE.

61,034.

Specification for Design.

Patented June 6, 1922.

Application filed May 31, 1921. Serial No. 473,931. Term of patent 7 years.

To all whom it may concern:

Be it known that I, THURE E. DAHL, a subject of the King of Sweden, residing at New York, in the county of New York and State of New York, in the United States of America, have invented a new, original, and ornamental Design for a Globe for Lighting Fixture, of which the following is a specification, reference being had to the accompanying drawing, forming part thereof.

Fig. 1 is a plan view of a portion of the top of a globe for lighting fixture, one-half of the ornamentation being shown.

Fig. 2 is a front view of the same.

I claim:

The ornamental design for a globe for lighting fixture, as shown.

THURE E. DAHL.
